(57) **CLAIM**

The ornamental design for a cap, as shown and described.

DESCRIPTION

FIG. 1 is a perspective view of a cap showing my new design.
FIG. 2 is a front elevational view of FIG. 1.

FIG. 3 is a right side elevational view of FIG. 1, the left side
elevational view being a mirror image thereof.

FIG. 4 is a rear elevational view of FIG. 1.

FIG. 5 is a top plan view of FIG. 1.

FIG. 6 is a bottom plan view of FIG. 1; and,

FIG. 7 is an exploded perspective view of FIG. 1.

The broken lines in FIGS. 1-7 are included for the purpose of
illustrating portions that form no part of the claimed design.
